UNITED STATES PATENT OFFICE.

ALBERT N. ANTHES, OF QUINCY, ILLINOIS, ASSIGNOR OF ONE-HALF TO ROBERT F. GUNTHER, OF QUINCY, ILLINOIS.

SELF-LUBRICATING SPRING.

Application filed August 30, 1923. Serial No. 660,177.

To all whom it may concern:

Be it known that I, ALBERT N. ANTHES, a citizen of the United States, residing at Quincy, in the county of Adams and State of Illinois, have invented a new and useful Self-Lubricating Spring, of which the following is a specification.

The object of my invention is to provide novel means for the self-lubrication of the leaf springs used on automobiles; and to provide novel means for interlocking the several leaves of the complete spring. I attain this and other objects of my invention by the mechanism illustrated in the accompanying drawings, in which—

Figure 1 is a top elevation of my invention;

Fig. 2 is a side elevation of same;

Fig. 3 is a top plan view of one of the intermediate leaves containing wicking, with an alternative form also shown in which the wicking is omitted;

Fig. 4 is a longitudinal section on line 4—4 of Fig. 1;

Fig. 5 is a transverse section on line 5—5 of Fig. 4;

Fig. 6 is a transverse section on line 6—6 of Fig. 4;

Fig. 7 is a transverse section on line 7—7 of Fig. 4;

Fig. 8 is a detail elevational view of bolt 12; and

Fig. 9 is a detail bottom plan view of a portion of one of the main leaves 3 and its guide element 10.

Like numerals indicate like parts in each of the several views.

Referring to the accompanying drawings I provide an uppermost main supporting leaf

40 1 and succeeding main supporting leaves 3 with intermediate leaves 2 interposed successively between the several main supporting leaves. All of the leaves are clamped together by clamp plates 4 and bolts 5, as shown in Figs. 1 and 4. The top clamp plate 4 is provided with a centrally positioned oil reservoir 6 opening into vertical oil passages 7 which are provided in aligned position in each of the main supporting leaves

45 1 and 3, as shown in Fig. 4. I provide in each of the intermediate leaves 2 a longitudinal slot 8 extending nearly the entire length of the leaves, as shown in Figs. 3 and 4. I may provide a wicking 9 for insertion in this slot, or the wicking 9 may be omitted en-

tirely when a hard oil or grease is used for lubrication.

The main supporting leaves, as shown in Figs. 4, 6, and 9, are provided with bottom guide projections 10 disposed at the portion 60 of the leaf in which the oil passage 11 is positioned, the projection 10 functioning both as a reinforcement of the spring at the portion containing the oil channel and also as a guide element to hold the spring in 65 alignment with the intermediate leaf 2 beneath as the guide element 10 seats or projects into the longitudinal slot 8 of leaves 2.

The ends of the uppermost main supporting leaf 1 are looped around in the customary 70 manner to receive bolt 12, which is mounted in a conventional bushing 20. Bolt 12 is provided with a longitudinal oil channel extending from its head to or slightly past approximately the center of the bolt. A 75 short radial oil channel 14 extending from channel 13 to the annular oil groove 15 as shown in Figs. 7 and 8 provides means for supplying lubricating oil to the leaf spring 4 at the ends thereof. A short diagonal oil 80 channel 16 extends from oil groove 15 through leaf 1 to slot 8 in the uppermost intermediate leaf 1, as illustrated in Fig. 4.

I provide a bottom lug or projection 18 on top clamp plate 4 to seat in the correspondingly shaped portion of spring leaf 1, and I provide a correspondingly shaped depression 19 in bottom plate 4 to receive the correspondingly depressed central portion 85 of the bottom main supporting leaf 3, as 90 illustrated in Fig. 4, each of the leaves being correspondingly depressed or downwardly curved at their central portions, thus interlocking the several leaves of the spring.

In using the invention lubricating oil may 95 be supplied to reservoir 6 where it will seep down through the oil passages 7. Lubricating oil may also be supplied to the oil channels 13 in the bolts 12, whence it will pass 100 through the radial oil passage 14 to the annular oil grooves 15 and thence through oil channels 16 to the longitudinal slot 18 in the uppermost intermediate spring 18 and thence 105 through the vertical oil passage 11 to the succeeding channel 8 of the next intermediate spring, and so on until the entire spring is lubricated. Where lubricating oil is used I prefer to provide the wicking 9 in the several channels 8; but if hard oil or grease is used, no wicking is required.

What I claim is:

1. In a self-lubricating spring, the combination of main supporting leaves having vertical oil passages, said leaves having projections on their under side surrounding said oil passages to reinforce the leaves and to function as guides, and intermediate leaves having longitudinal slots extending substantially the entire length of the leaves and 10 functioning as oil passages and also as means for engaging the above-mentioned guides of the main supporting leaves.
2. In combination with mechanism described in claim 1, longitudinally channelled 15 bolts in the ends of the uppermost main supporting leaf, said bolts having a radial oil passage and an annular oil groove, the leaf having an oil passage extending from

the annularly grooved portion of the bolt to the longitudinal slot of the intermediate 20 leaf next beneath.

3. In a self-lubricating spring, the combination of main supporting leaves having vertical oil passages, intermediate leaves alternating with the main supporting leaves, 25 each of said intermediate leaves having a longitudinally extending slot extending substantially the length of the entire leaf and aligned with the vertical oil passages of the main supporting leaves to permit oil to 30 seep from one leaf to the other, and means for admitting oil to the uppermost intermediate leaf at the central and near the end portions thereof.

ALBERT N. ANTHES.
